UNITED STATES PATENT OFFICE.

DARWIN HANAUER, OF LA GRANGE, ILLINOIS, ASSIGNOR TO THE ROME COMPANY,
INC., A CORPORATION OF NEW YORK.

DETACHABLE COVER FOR BEDSPRINGS.

Application filed December 29, 1927. Serial No. 243,271.

Bed springs made of vertical coils connected together by small helical springs have to a large extent displaced the expensive so-called box springs whose only advantage 5 thereover is that they are completely enclosed in a cover and prevent the entry of lint, threads and the like into the springs, as well as some of the dust that would otherwise accumulate in the springs; the open coiled bed 10 springs being unprotected against the entry of dust and other foreign matter and being difficult to clean when such matter collects on the coils.

The object of the present invention is to 15 produce a simple and novel cover for a bed spring of the vertical spring type, which shall prevent the entry of dust and other foreign matter into the coils at least as effectively as this is done by the covering of a 20 box spring.

When a covering is employed it should be made detachable so that it can be removed and washed when soiled. A further object of the present invention is to produce a cover 25 for a bed spring of the vertical spring type that may be quickly and easily applied or removed and which will fit snugly, without special effort on the part of the person placing it on a spring, when in position on the 30 spring.

The various features of novelty whereby my invention is characterized will herein-after be pointed out with particularity in the 35 claims; but, for a full understanding of my invention and of its objects and advantages, reference may be had to the following detailed description taken in connection with the accompanying drawing, wherein:

Figure 1 is a top plan view of one of my 40 improved covers applied to a bed spring, only fragments of the spring being shown; Fig. 2 is a perspective view, on a larger scale than Fig. 1, of one end of the cover; and Fig. 3 is a bottom plan view of a fragment of the 45 cover in the vicinity of the opening in the latter; and Fig. 4 is a plan view, on a small scale, of a modification.

Referring to the drawing, 1 represents a 50 coil bed spring of any usual or suitable construction. My improved cover consists of a fabric box-like structure adapted to fit closely upon the spring. When a mattress is placed on the spring it serves as a cover for the top of the latter, and my improved device may 55 therefore be made open on the upper side.

However, for the purpose of holding the device in place on the spring, the top thereof is preferably made in the form of a border or frame attached to the side and end walls.

The device may be made of any desired 60 number of pieces sewed together to form the bottom 2, side walls 3 and end walls 4. The frame-like top consists of side elements 5 and end elements 6 that will usually be about 65 as wide as the height of the side and end walls.

In order to permit the cover to be completed before it is applied to the spring, and yet permit it to fit snugly upon the spring when in place, I divide the cover along a line 70 extending through one of the top frame elements, the adjacent upright wall of the structure, and extending a short distance into the bottom wall. When the cover is for a rectangular spring, I prefer to divide it at one 75 of the ends as shown. When the line of division extends into the end through the bottom for a distance about equal to the width of the top element 6, this end of the cover may be opened far enough to permit the spring to 80 be inserted. Then, when the meeting edges of the divided members of the cover are drawn together and fastened, the cover will be fitted snugly about the frame. Any suitable means may be employed for drawing the 85 meeting edges together and holding them, although I prefer to use one of the common types of fastenings consisting of two cooperating rows of interlocking hooks, as indicated at 7; thus permitting what may be termed the 90 mouth of the cover to be quickly opened or closed by the mere drawing of the finger piece 8 along the line of the hooks. I have not shown the details of this particular fastening 95 since they are well known.

It will thus be seen that I have produced a simple cover that may be manufactured so as accurately to fit over a spring and to be quickly and easily applied by anyone.

If it is desired completely to enclose the 100 spring, a flap such as indicated at 9 in Fig. 4 may be provided to close the opening in the frame-like top of the cover. This flap may be sewed to one end element of the frame, as indicated at 10, and be detachably fastened 105 to the other end element and to the side elements by snap fasteners 11, or the like.

While I have illustrated and described with 110 particularity only a single preferred form of my invention, I do not desire to be limited to

the exact structural details thus illustrated and described; but intend to cover all forms and arrangements which come within the definitions of my invention constituting the 5 appended claims.

I claim:

1. A cover for a coil-bedspring or a spring cushion or the like comprising a box-like structure of flexible material of a size and 10 shape to fit about the spring or the like, the top of the box-like structure being in the form of a frame connected at its edges to the tops of the sides of the box, said structure being divided along a line extending transversely 15 of and completely across one of the elements of said frame and down the adjacent side and for a short distance into the bottom, and means for detachably securing together the meeting edges of the structure along the line 20 of division.
2. A cover for a coil-bedspring or a spring cushion or the like comprising a box-like structure of flexible material of a size and shape to fit about the spring or the like, the 25 top of the box-like structure being in the form of a frame connected at its edges to the tops of the sides of the box, said structure being divided along a line extending transversely of and completely across one of the elements 30 of said frame and down the adjacent side and for a short distance into the bottom, and means for detachably securing together the meeting edges of the structure along the line of division, a flap for closing the opening in

the frame secured to a frame element other 35 than the one that is divided and detachably secured to the other frame elements.

3. A cover for a rectangular coil bed spring or a spring cushion or the like comprising a box-like structure of flexible material of a 40 size and shape to fit about the spring, the top of the box-like structure being in the form of a frame connected at its edges to the tops of the sides of the box, said structure being divided along a line extending transversely of 45 and completely across one of the elements of said frame at about the middle of the latter down the adjacent side and for a short distance into the bottom, and means for detachably securing together the meeting edges of 50 the structure along the line of division.

4. A cover for a coil-bedspring or a spring cushion or the like comprising a box-like structure of flexible material of a size and shape to fit about the spring or the like, the 55 top of the box-like structure being in the form of a frame connected at its edges to the tops of the sides of the box, said structure being divided along a line extending transversely of and completely across one of the 60 elements of said frame and down the adjacent side, and means for detachably securing together the meeting edges of the structure along the line of division.

In testimony whereof, I sign this specification. 65

DARWIN HANAUER.
